Primary Examiner — Rebekah A Caruso

(57) **CLAIM**

The ornamental design for a phone grip with stand, as shown and described.

DESCRIPTION

1.1 is a perspective view of a phone grip with stand showing our new design;

1.2 is a front perspective view thereof;

1.3 is a back perspective view thereof;

1.4 is a bottom perspective view thereof;

1.5 is a top perspective view thereof;

1.6 is a right-side perspective view thereof; and

1.7 is a left-side perspective view thereof.

The broken lines represent portions of the article that form no part of the claimed design.
